Primary Examiner — Darlington Ly*Assistant Examiner* — Daniel J Domino(74) *Attorney, Agent, or Firm* — Oblon, McClelland, Maier & Neustadt, L.L.P.(57) **CLAIM**

The ornamental design for a control board device with graphical user interface, as shown and described.

DESCRIPTION

FIG. 1 is a front view of a control board device with graphical user interface showing our new design;

FIG. 2 is a back view thereof;

FIG. 3 is a top view thereof;

FIG. 4 is a bottom view thereof;

FIG. 5 is a right side view thereof;

FIG. 6 is a left side view thereof; and,

FIG. 7 is an enlarged view of the display screen portion of FIG. 1.

The broken lines in the drawings illustrate portions of the control board device with graphical user interface that form no part of the claimed design.

1 Claim, 7 Drawing Sheets(56)
